UNITED STATES PATENT OFFICE.

THADDEUS S. BARLOW, OF NEW YORK, N. Y.

MEANS FOR CONTROLLING THE GAS PILOT LIGHTS OF WATER-GAS MACHINES.

Application filed May 24, 1921. Serial No. 472,045.

To all whom it may concern:

Be it known that I, THADDEUS S. BARLOW, a citizen of the United States, and a resident of the city of New York, borough 5 of Manhattan, county and State of New York, have invented certain new and useful Improvements in Means for Controlling the Gas Pilot Lights of Water-Gas Machines, of which the following is a full, 10 clear, and exact description.

The present invention relates to means for controlling the gas pilot light of water gas machines.

One object of the invention is to provide 15 means whereby the pilot light of the superheater may be reduced when the stack valve is closed and increased upon the opening of the stack valve or during a "blow." In water gas machines it is customary to employ 20 a gas light adjacent to the take-off opening, which light is kept burning at all times for the purpose of consuming combustible gases which are discharged during the "blow," and also such combustible gases as 25 may leak from the stack valve when closed. Not only is such a light used for the purpose of igniting combustible gases discharged from the stack or which leak therefrom, but it is also necessary to enable the 30 operator to determine whether or not he is using enough secondary air during the "blow." Such lights referred to herein as a "pilot light," as heretofore used, have employed 35 a constant flow and a constant flame at all times, and no effort has been made so far as I am advised of the prior state of the art, to reduce the quantity of gas consumed by such lights or burners during the "run" or when the stack valve is closed. 40 The result, therefore, has been that such burners consume more gas than is required.

A further object of the invention therefore, is to provide means whereby the flow 45 of gas to the pilot light may be controlled by interconnecting mechanism operated by the means employed to open and close the stack valve, so arranged that as the stack valve is opened the flow of gas to the pilot light and the flame produced thereby will be increased, and when the stack valve is closed the flow of gas to the pilot light and the flame produced thereby will be decreased.

A further object is to provide a guard for 50 the burner so constructed as to prevent the

accidental extinguishment of the pilot light at all times and especially during the "blow," when the velocity of the issuing combustible or inert gases is greatest, permitting the use of a smaller flame during the 60 "blow."

The invention therefore consists of a burner located adjacent to the stack valve opening with means to supply gas to said burner, and means to control the supply of 65 gas thereto to reduce or increase the flow and flame, with a guard surrounding and protecting the said burner.

The invention further consists of a gas burner located adjacent to the stack valve 70 opening and means whereby the flow of gas to said burner may be automatically controlled, and whereby it shall be increased upon the opening of the stack valve and decreased upon the closing of the stack valve. 75

The invention further consists of a burner located adjacent to the stack valve opening, and means whereby the flow of gas to said burner is controlled directly by the means controlling the opening and closing of the 80 stack valve, and it further consists of the devices and combinations of devices which will be hereinafter described and claimed.

The invention is illustrated in the accompanying drawing in which Fig. 1 is a view 85 in perspective and shows the upper part of the superheater of a water gas machine with my invention applied thereto.

Fig. 2 shows an enlarged view of the burner and its guard, portions being shown 90 in diametrical vertical section extending longitudinally through the burner and guard.

Fig. 3 shows in elevation one form of 95 throttle valve which may be used to control the flow of gas and the flame produced by the burner.

Similar reference characters will be employed throughout the specification and drawing to designate corresponding parts. 100

Referring to the drawing, (a) shows the upper portion of a superheater of a well-known water gas making machine; (b) is the take-off T having an opening (c); and (d) is a flaring shield surrounding the upper open end of the take-off T (b). The opening (c) is adapted to be closed by a valve (e) which valve is carried by a rock shaft (f) mounted in bearings (g) and rotated therein by any suitable means, as by 105 110

means of the crank (h), whereby the valve (e) is raised or lowered to open or close the opening (c) in the take-off (b). The flaring shield (d) is cut out as shown at (i) to permit the freedom of movement of the cover (e), and as usual in such devices a conductor (j) leads from the branch or stem of the take-off T (b) to conduct the illuminating or combustible gas to a gas holder or 10 any other apparatus intermediate the gas generator and the gas holder. In the operation of such an apparatus it is required that the valve (e) be frequently operated to close or open the take-off T (b) it being closed 15 during the "run" of the apparatus and open during the "blow" of the apparatus.

It has been found necessary to maintain a lighted burner in close relation to the take-off T opening or stack valve, for the 20 purpose of igniting the combustible gases discharged from the opening in the stack either during the "run" caused by leakage, or while "blowing," and obviously this gas flame must be lighted at all times and there 25 must be no danger of its accidental extinguishment, so that it has been customary to maintain a relatively large flame, one not easily extinguished by a blast, and this has been the cause of considerable loss and expense. Inasmuch as a relatively small flame 30 is sufficient to take care of the leakage of combustible gas when the stack valve is closed, I have provided means whereby during the "running" period, or while the stack valve 35 is closed, the gas flame and supply of gas to the burner is materially reduced and automatically increased when the stack valve is raised or during the "blowing" operation.

For this purpose I provide a burner (1), 40 fitted within a guard (2), the burner and guard passing through the shield (d) as indicated in Fig. 1 in the drawing, wherein the shield (d) is shown broken away to illustrate the position of the burner and guard with relation to the shield and stack opening. The burner is carried at the forward end of 45 a pipe (3) which pipe receives combustible gas from any suitable source of supply. The pipe (3) is fitted with a valve (4) provided with any usual form of closure whereby the flow of gas to the burner may be reduced or increased as desired. In the illustrated embodiment the valve (4) has a cut-off (5) provided with a small aperture or by-pass (6). As this form of valve is one well-known, it is unnecessary to further describe it. The valve is operated by means of a lever arm (7) pivotally connected to a link (8) which in turn is pivotally connected to an 50 arm (9) which is fixedly attached to the rock shaft (f) by means of a clamp (10). The foregoing arrangement is such that the rocking of the shaft (f) to raise and lower the stack valve (e) will automatically operate the valve (4) to increase or reduce the

flow of gas to the burner (1); it being understood that it is so assembled that as the rock shaft (f) is turned to raise the stack valve (e) and open the take-off T (b) the flow of gas to the burner will be increased, 70 and as the rock shaft (f) is turned to close the take-off T (b) the flow of gas will be reduced. The result of the foregoing arrangement is that while there is a light constantly burning in close proximity to the opening (c) the flow of gas to the burner and the flame will be materially reduced when the stack valve (e) closes the opening (c) while still leaving a flame burning of sufficient volume to ignite the leakage of combustible gas, and when the stack valve (e) is opened during the "blowing" operation, the flow of gas to the burner (1) and the flame produced in the guard (2) will be materially increased. 80

The guard (2) consists of a casting which may be cylindrical in cross section as shown, and it is open at each end, one end being connected by means of the arms (11) to a boss (12) interiorly screw-threaded as at 90 (13) whereby the guard may be affixed to the threaded portion (14) of the pipe (3) carrying the burner (1). A suitable lock nut (15) is provided whereby the guard may be held in adjusted position on the pipe (3) 95 with the burner (1) projecting to a greater or less extent within the open chamber (16) of the guard (2). As shown in Fig. 2 of the drawing, the burner (1) projects for some distance within one end of the guard (2) 100 sufficiently so that the accidental extinguishment of the flame is prevented. In order to insure that air and discharged gases, or a blast, shall not pass through the guard (2) with sufficient force to extinguish the flame 105 of the pilot light, I have provided within the chamber (16) of the guard (2) baffle plates (17) which project from the interior surface in a forward direction at an angle of substantially 45 degrees, each covering 110 slightly more than one-half of the diameter of the chamber (16), and as shown, these baffle plates (17) project forwardly and extend from opposite surfaces so that their free edges overlap and cross a line corresponding to the central horizontal axial diameter. By this arrangement the flame may readily pass between the baffle plates and project at the outer end of the guard (2), but will be protected from any air or 115 blast which may enter the guard (2); thus the flame will be effectively protected from accidental extinguishment.

In the operation of the apparatus the take-off T is opened or closed in the usual manner during the "run," and for the purpose of "blowing," and obviously as the stack valve operating mechanism is operated, the valve will be operated simultaneously therewith by means of the inter- 120 125 130

connecting mechanism, whereby the flow of gas to the burner will be increased as the stack valve is raised, and decreased as the stack valve is lowered; thus increasing and diminishing the size of the flame, leaving at all times, however, a flame of sufficient size to ignite the combustible gas which might be likely to escape during the "run," while during the "blowing" operation with the stack valve open, the flame will be materially increased so as to insure the burning of the combustible gases which issue at high velocity.

Having described the construction, organization, and mode of operation of my invention as illustrated, I claim:

1. In combination with a water gas machine, a gas burner located adjacent the take-off T opening, means for conducting a supply of gas to the said burner, and means for regulating the flow of gas to said burner so as to increase or diminish the same as the stack valve is opened or closed.

2. In combination with a water gas machine, a gas burner located adjacent the take-off T opening, means for conducting a supply of gas to said burner, and means for automatically regulating the flow of gas to said burner so as to increase or diminish the same as the stack valve is opened or closed.

3. In combination with a water gas machine, a gas burner located adjacent the take-off T opening, means for conducting a supply of gas to said burner, a valve for regulating the flow of gas to said burner, and connections between the means for opening and closing the take-off T and the said valve, whereby the valve is operated by the stack valve operating means.

4. In combination with a water gas machine, a gas burner located adjacent the take-off T opening, means for regulating the flow of gas to said burner so as to increase

or diminish the same as the take-off T is opened or closed, and a guard surrounding the said burner, said guard provided with means for preventing the extinguishment of the flame.

5. In combination with the take-off T of a water gas machine, a gas burner in said T, means for regulating the supply of gas thereto to increase or diminish the flame, a cylindrical guard surrounding the said burner, said guard being open at each end and provided upon its inner surface with baffle plates extending in an inclined direction towards one end from opposite surfaces, the free edges of the baffle plates overlapping a longitudinal axial line.

6. In combination with the take-off T of a water gas machine, a gas burner in said T, means for regulating the supply of gas thereto to increase or diminish the flame, a guard surrounding the said burner, said guard being open at each end and provided upon its inner surface with a baffle plate extending partially across the chamber within said guard.

7. In combination with the take-off T of a water gas machine, a burner having its outlet in communication with said take-off to ignite gas passing through the take-off, and guard means between the tip of the burner and the interior of the T to prevent a draft in the take-off from extinguishing the burner.

8. In combination with the take-off of a gas machine, a valve for closing the take-off, opening means for said valve, and a pilot light for igniting gas in said take-off; means dependent on the opening and closing of said valve to regulate the flow of gas to said pilot light and to increase the supply with the opening of said valve and decrease the supply with the closing of the valve.

THADDEUS S. BARLOW.
